BOBBIN CLUTCH

Application filed April 3, 1931. Serial No. 527,599.

This application is a continuation in part of application, Serial No. 353,428, filed April 8, 1929.

This invention relates to a clutch by which a bobbin may be centered on a spinning or twisting spindle and frictionally rotated thereby.

It is the general object of my invention to provide a bobbin clutch of an improved and simplified construction, by which the bobbin may be accurately centered with respect to the axis of the spindle and by which it may be rotated with the desired driving force.

15 A further object of my invention is to provide a bobbin clutch which has relatively few and simple parts, all of which may be easily and economically manufactured. The clutch thus constructed is reliable and certain in operation and is exceptionally free from accidental breakage of parts when in use.

25 My invention further relates to arrangements and combinations of parts which will be hereinafter described and more particularly pointed out in the appended claims.

In the drawings:

Fig. 1 is an elevation, partly in section, of portions of a spindle embodying my improvements;

Fig. 2 is a side elevation of a casing member;

Fig. 3 is a plan view of certain parts, looking in the direction of the arrow 3 in Fig. 1;

Figs. 4 and 5 are side and front elevations of one of the spring clutch fingers;

Fig. 6 is a plan view of the retaining cap;

Fig. 7 is a view similar to Fig. 1 but showing a modified form of construction;

Fig. 8 is a section along the line 8—8 of Fig. 7;

Fig. 9 is a combined view illustrating in front and in edge elevation a contact segment;

Fig. 10 is a central vertical section through the clutch shown in Fig. 7, illustrating a bobbin mounted thereon; and

Fig. 11 is a side elevation, partly in sec-

tion, of the casing forming a part of the clutch illustrated in Figs. 7 to 10.

Referring to Figs. 1 to 6 of the drawings, I have shown a spindle comprising a blade 10 having a whirl 11 fixed thereon. The whirl 11 is preferably provided with an upwardly projecting end or hub portion 12 and with an annular recess 13 in its upper face.

A casing member 15 is firmly mounted on the blade 10 above the whirl 11 and is slotted in its lower portion, as indicated at 16, thus providing depending parts 18 which extend downward and engage the bottom of the annular recess 13 when the parts are assembled.

Spring clutch fingers 20 are formed as indicated in Figs. 4 and 5, the fingers being in general substantially L-shaped, with laterally projecting arms 21 at their lower ends and with offset projections 22 at their upper ends.

In assembling the parts, the fingers 20 are inserted in the slots 16 and the offset ends 22 of the fingers project upward into a recess 24 above the slots 16. A retaining member or cap 26 is then forced downwardly over the periphery of the whirl 11 and engages the outwardly projecting portions 21 of the spring fingers.

The fingers 20 are so shaped that such engagement by the cap 26 places the upper portions of the fingers 20 under tension, said upper ends being firmly pressed outward as far as is permitted by the engagement of the projections 22 with the flange 25 surrounding the recess 24.

The fingers 20 are formed of resilient material, preferably steel, which is hardened and tempered after the fingers are shaped. When the bobbin B is placed on the blade 10 and is forced downward, the fingers 20 will be engaged by the inner wall 30 of the butt of the bobbin and will be forced slightly inward to the position indicated in Fig. 1, in which position they will firmly center the bobbin and will provide the desired frictional driving engagement therewith. Each of the fingers is independently formed and separately movable, with features contribute

largely to the accurate centering of the bobbin.

In the modification shown in Figs. 7 to 11, the clutch is illustrated as comprising an axially spaced casing and whirl members 31 and 32 affixed to the blade 33 in axially spaced relation and having opposed recesses 34 and 36 respectively. In this form of the invention the resilient means or spring members comprise substantially flat or leaf springs bent into an approximately L-shape form to provide integral arms 37 and 38 which diverge preferably at an acute angle. The arms 38 are adapted to seat in the annular recess 36 and are clamped firmly in this recess by the retaining upper flange of the cap member 39 which is secured to the whirl preferably by being a driving fit thereon. Thus the upper flange of the cap member and base of the recess 36 provide opposed clamping surfaces which maintain the outwardly directed arms 38 of the spring members substantially fixed upon and rigid with the whirl and therefore rigid with the blade 33.

The contact segments 41 have their upper ends curved inwardly to provide upwardly directed lips 42 which extend within the annular recess 34 in the casing member and are retained in this recess by the depending annular wall thereof. The lower ends of these contact segments fit within the circular opening in the top flange or wall of the cap member 39 and have their outward movement limited by this portion of the cap member. Preferably the casing 31 is of the type illustrated in Fig. 11 in which slots 43 extend longitudinally toward the whirl for receiving the contact segments, the material forming these slots providing fingers 44 which maintain the contact segments in circumferentially spaced relation about the blade. The lower ends of the fingers 44 extend to a position slightly below and within the opening in the top wall of the cap member 39 and the slots 43 are formed to fit closely about the contact segments 41 so as to be effective for guiding the latter for movement toward and from the blade in an approximately radial direction.

The arms 37 of the springs extend longitudinally of the blade behind the contact segments and incline upwardly toward the latter, these arms engaging the segments at points intermediate the ends thereof. Preferably the arms 37 are proportioned to terminate toward the upper ends of the segments at the points where engagement is effected as this provides relatively long and resilient spring arms which have smooth and easy and yet firm engagement, providing a very desirable clutching action. While the longitudinal arms 37 of the spring preferably have their free ends in direct engage-

ment with the segments intermediate the ends of the latter and these arms are inclined with respect to the axis of the blade to render this engagement more effective, it will be evident that in some instances it may be desirable to have the arms 37 extend substantially parallel to the blade, in which event they may be provided with lugs or other protuberances, as with outturned end portions, for engagement with the segments.

In assembling the apparatus of the type disclosed in Figs. 7 to 11 inclusive, the spring members 37 are disposed about the whirl with their outwardly directed arms 38 properly spaced in the annular recess 36 in the upper surface of the whirl. The cap member 39 is then applied and caused firmly to engage these arms 38 and to clamp the same securely to the whirl. The casing 31 is then applied to the blade 33 and positioned so that the lower ends of the fingers extend within the circular opening in the top of the cap member and the spring arms 37 project upwardly and outwardly into the slots 43. The segments 41 may then be applied by pushing the upper ends of these segments into the slots and across the free upper ends of the spring arms 37, bending the latter inwardly and then pressing on the lower portions of the segments to cause the free lower ends thereof to enter the space between the circular opening in the cap 39 and the associated spring member.

All parts of the bobbin clutch may be cheaply and easily manufactured and the spring fingers may be easily removed and replaced if for any reason renewal becomes necessary.

From the foregoing it will be apparent that in each modification the springs have their outwardly disposed legs maintained substantially rigid with the blade due to the clamping action of the cap and the whirl, and this manner of mounting the outwardly disposed arms causes the longitudinal or upwardly directed arms to exert an outward or approximately radial pressure which is applied to the bobbin for retaining the latter. Thus, while in one instance the springs have direct engagement with the bobbin chamber and in the other instance these springs act on the segments to cause the latter to engage the bobbin, in each case advantages of the springs are embodied in the new structure, resulting in the improved mode of operation. The outward movement of the free upper ends of the fingers is limited by the casing in each embodiment, by direct engagement with the casing in the first embodiment and by indirect engagement through the segments in the second embodiment.

It should be understood that the present disclosure is for the purpose of illustration

only and that this invention includes all modifications and equivalents which fall within the scope of the appended claims.

I claim:

5. 1. In a spindle clutch construction comprising a blade, a contact segment disposed longitudinally of the blade, and means for supporting the contact segment for movement toward and from the blade and for 10 limiting outward movement of the contact segment relative to the blade, the combination of a unitary spring member comprising diverging arms, one arm being disposed approximately longitudinally between the 15 blade and the contact segment and engaging the latter, the other arm extending outwardly beyond the contact segment, and means for holding the latter arm substantially rigid with the blade, whereby the longitudinally disposed arm may be caused to 20 bear against the contact segment with a yielding pressure.
2. In a spindle clutch construction comprising a blade, a contact segment disposed longitudinally of the blade, and means for supporting the contact segment for movement toward and from the blade and for 25 limiting outward movement of the contact segment relative to the blade, the combination of a unitary spring member, comprising arms diverging at an acute angle, one arm extending longitudinally of the blade and between the latter and the contact segment, this arm inclining outwardly from the 30 blade and engaging the segment, the other arm extending outwardly beyond the contact segment substantially radially of the blade, and means for holding the latter arm substantially rigid with the blade, whereby 35 the longitudinally disposed arm may be caused to bear against the contact segment with a yielding pressure.
3. In a spindle clutch comprising a blade, a whirl mounted thereon, contact segments disposed longitudinally of the blade and spaced about the latter, and means for retaining the segments and for supporting the same for movement transversely of the blade, the combination of means for urging 40 the segments outwardly comprising resilient arms extending longitudinally of the blade and spaced circumferentially thereabout for engagement with the segments, each resilient arm having a base portion united therewith and extending outwardly of the blade, and means for securing the base portions to the whirl, so that the arms may be caused to bear with a yielding pressure on the segments.
4. In a spindle clutch comprising a blade, a whirl mounted thereon, contact segments disposed longitudinally of the blade and spaced about the latter, and means for retaining the segments and for supporting the same for movement transversely of the blade,
- the combination of means for urging the segments outwardly comprising resilient arms extending longitudinally of the blade and spaced circumferentially thereabout for engagement with the segments, a base portion carried by each resilient arm and extending outwardly of the blade, and means for mounting the base portions firmly on the whirl, whereby the resilient arms may be caused to bear with a yielding pressure on the segments.
5. In a spindle clutch comprising a blade, a whirl mounted thereon, contact segments disposed longitudinally of the blade and spaced about the latter, and means for retaining the segments and for supporting the same for movement transversely of the blade, the combination of means for urging the segments outwardly comprising spring members having unitary diverging arms, one arm of each spring member being disposed longitudinally of the blade and in engagement with a segment, the other arm of each spring member extending outwardly across the whirl, and means for securing the latter arms to the whirl, whereby the first-mentioned arms may be caused to bear with a yielding pressure on the segments for urging the latter outwardly.
6. In a spindle clutch comprising a blade, a whirl mounted thereon, contact segments disposed longitudinally of the blade and spaced about the latter, and means for retaining the segments and for supporting the same for movement transversely of the blade, the combination of means for urging the segments outwardly comprising spring members having unitary diverging arms, one arm of each spring member being disposed longitudinally of the blade and inclined outwardly toward a segment for engagement therewith, the other arm of each spring member extending outwardly at an acute angle to the longitudinal arm and across the whirl, and means for securing the outwardly extending arms to the whirl, whereby the first-mentioned arms may be caused to bear with a yielding pressure on the segments for urging the latter outwardly.
7. A spindle clutch comprising a blade, whirl and casing members mounted thereon in axially spaced relation, these members having opposed recesses therein, contact segments disposed longitudinally about the blade and mounted in the opposed recesses of the whirl and casing members, a spring member associated with each segment and comprising a resilient arm extending longitudinally of the blade and between the latter and the segment, each of these arms extending outwardly from the blade to engage the segment with which it is associated, a base portion unitary with each of these arms and extending outwardly across the whirl beyond the segment, and means for maintain-

ing each base portion firmly mounted on and substantially rigid with the whirl, whereby the resilient arms may be maintained effective for urging the segments outwardly.

5 8. A spindle clutch comprising a blade, whirl and casing members mounted thereon in axially spaced relation, these members having opposed recesses therein, contact segments disposed longitudinally about the

10 blade and mounted in the opposed recesses of the whirl and casing members, a spring member associated with each segment and comprising a resilient arm extending longitudinally of the blade and between the latter

15 and the segment, each of these arms terminating intermediate the ends of the segment with which it is associated and inclining outwardly from the blade and having its free end portion bearing against the segment, a base portion unitary with each of

20 these arms and extending outwardly across the end of the segment and across the whirl beyond the segment, and means for maintaining each base portion firmly mounted

25 on and substantially rigid with the whirl, whereby the resilient arms may be maintained effective for urging the segments outwardly.

9. A bobbin clutch comprising a blade, a 30 whirl on the blade, a casing mounted on the blade with longitudinal slots in its periphery, mechanism acting through the slots for frictionally holding a bobbin, said mechanism including spring fingers, and clamp-

35 ing means at the upper end of the whirl for clamping the spring fingers between the end of the whirl and the clamping means, said mechanism including parts which project upwardly inside the upper edges of said

40 slots to limit the action of said spring fingers.

10. A bobbin clutch comprising a blade, a whirl on the blade, a casing mounted on the blade with depending fingers defining longitudinal slots therebetween, mechanism acting

45 through the slots for frictionally holding a bobbin, said mechanism including spring fingers, and clamping means at the upper end of the whirl for clamping the spring fingers between the end of the whirl and the

50 clamping means, the whirl having integral spacing means projecting upwardly from its upper end close to the blade for holding said mechanism in spaced relation to the blade, and said casing fingers projecting downwardly between said clamping and spacing means.

11. A bobbin clutch comprising a blade, a whirl on the blade, a casing mounted on the blade with depending fingers defining longitudinal slots therebetween, mechanism for frictionally holding a bobbin, said mechanism including L-shaped spring fingers,

60 clamping means at the upper end of the whirl for clamping said spring fingers between the end of the whirl and the clamping

means, and means projecting upwardly and engaging the inner edges of the casing for limiting the action of said spring fingers.

12. A bobbin clutch comprising a blade, a whirl on the blade, a casing mounted on the blade having longitudinal slots in its periphery, mechanism acting through said slots for frictionally holding a bobbin, said mechanism including spring means, and clamping means at the upper end of the whirl for clamping the spring means between the end of the whirl and the clamping means, and means for limiting the action of said spring means.

13. A bobbin clutch comprising a blade, a whirl on the blade, a casing mounted on the blade having longitudinal slots in its periphery, and mechanism acting through said slots for frictionally holding a bobbin, said mechanism including contact surfaces movable radially of said blade through said slots and normally arranged to engage the inner periphery of the bobbin and spring means for controlling said surfaces, a cap on the end of the whirl, said cap pressing said spring means toward the whirl to cause the spring means yieldingly to hold said contact surfaces in position to engage the bobbin, and means for limiting the outward movement of said contact surfaces relative to said blade.

14. A bobbin clutch comprising a blade, a whirl mounted on the blade, a casing mounted on the blade with depending fingers defining longitudinal slots therebetween, mechanism for frictionally holding a bobbin, said mechanism including contact surfaces movable radially of the blade through said slots and resilient means for yieldingly holding said contact surfaces in position to engage the inner periphery of the bobbin, clamping means mounted on the upper end of the whirl, said clamping means pressing said resilient means toward the whirl and holding the same in position, and means for limiting the outward movement of said contact surfaces relative to the blade.

15. A bobbin clutch comprising a blade, a whirl mounted on the blade, a casing mounted on the blade with depending fingers defining longitudinal slots therebetween, mechanism for frictionally holding a bobbin, said mechanism including contact surfaces movable radially of the blade through said slots and resilient means for urging said contact surfaces outwardly through said slots, a cap mounted on the upper end of the whirl having an interior flange pressing said resilient means toward the upper end of the whirl, said cap holding said resilient means in position yieldingly to urge said contact surfaces outwardly against the inner periphery of the bobbin, and means for limiting the outward movement of said contact surfaces relative to said blade.

16. A bobbin clutch comprising a blade, a whirl mounted on the blade, a casing mounted on the blade with depending fingers defining longitudinal slots therebetween, and mechanism for frictionally holding a bobbin, said mechanism including contact members fulcrumed at the upper end of the whirl to move radially of the blade through said slots, said members having parts which project upwardly inside the upper edges of said slots to limit the outward movement of said members, resilient means for urging said contact members outwardly through said slots, and a cap mounted on the upper end of the whirl having an interior annular flange pressing said resilient means toward the upper end of the whirl, said cap holding said resilient means in position yieldingly to urge said contact members outwardly against the inner periphery of the bobbin.

Signed by me at Whitinsville, Massachusetts this 31st day of March, 1931.

GEORGE H. MAGRATH.
